UNITED STATES PATENT OFFICE.

VICTOR E. ANDERSON, OF WEST ALLIS, WISCONSIN, ASSIGNOR TO ALLIS-CHALMERS MANUFACTURING COMPANY, OF MILWAUKEE, WISCONSIN, A CORPORATION OF DELAWARE.

HYDRAULIC MACHINE.

Application filed June 28, 1926. Serial No. 118,936.

This invention relates in general to improvements in the construction and operation of hydraulic machines, and relates more specifically to improved mechanism for operating the inlet guide vanes of hydraulic turbines or the like.

An object of the invention is to provide new and useful improvements in hydraulic machines whereby the construction thereof is simplified and the operating efficiency thereof is enhanced.

It is common practice in the construction of hydraulic turbines of the reaction type, to operate an annular series of pivotally supported inlet guide vanes, by means of one or more fluid pressure actuated servo-motors arranged to simultaneously adjust all of the vanes. These servo-motors, in accordance with the prior practice, have been mounted upon the pit rings of the units thereby necessitating the provision of relatively heavy pit ring castings. With the prior arrangements of servo-motors, it was not only necessary to provide relatively heavy pit rings in order to withstand the pressure and to provide substantial supports for the servo-motors, but it was also necessary in some instances to make the pit of relatively large diameter, in order to accommodate the mounting of the servo-motors. The disposition of the servo-motors upon the pit ring walls, also provided undesirable obstructions which hindered access to the gate riggings.

The present invention comprises means whereby these objectionable features of the prior servo-motor mountings, are entirely eliminated. In accordance with the improvement the servo-motors are mounted directly upon the turbine casing within the annulus of the inlet guide vanes. Such disposition of the servo-motors not only enables the use of a relatively light pit ring liner, but permits reduction of the pit diameter to a minimum while still permitting free access to all portions of the gate riggings. The reaction resulting from operation of the inlet guide vanes is taken up directly in the turbine structure and need not be transmitted through adjacent structure such as pit ring liners. These and other advantages of the present improvement will appear from the following description.

A clear conception of an embodiment of the invention may be had by referring to the drawing accompanying and forming a part

of this specification in which like reference characters designate the same or similar parts in the several views.

Fig. 1 is a central vertical section through a vertical hydraulic turbine of the reaction type, having the inlet guide vane actuating servo-motors mounted upon the top casing or cover of the unit.

Fig. 2 is an enlarged fragmentary part sectional top view of the improved gate rigging.

The hydraulic turbine unit specifically illustrated in the drawing, comprises in general a high-speed axial flow rotor 2 secured to the lower end of a vertical main shaft 25, and housed within a casing comprising an upper casing or cover plate 7 and a lower casing section 9. The inlet side of the rotor 2 is in open communication with a vane free transition space 5 which communicates with a water supply conduit 3 past the annular series of adjustable inlet guide vanes 6, and through a speed ring 26. The cover plate 7 provides a support for a guide wall 8 extending downwardly into the transition space 5 and providing a housing for a guide bearing 27 associated with the shaft 25. The discharge end of the rotor 2 is in open communication with a draft tube 4, this draft tube being formed in the foundation 10 which also provides a support for the casing elements and for the speed ring 26.

The adjustable inlet guide vanes 6 are supported upon pivots 11 which are journaled in the cover plate 7 and in the lower casing portion 9 in a well known manner. The upper extremities of the pivots 11 are connected with an adjusting ring 14 through arms 12 and links 13, the ring 14 being rotatably supported upon the cover plate 7 and having inwardly projecting lugs 23 at diametrically opposite portions thereof. A pair of servo-motors each comprising a cylinder 17 and a piston 16 reciprocable therein, are rigidly attached to a supporting bracket 18 which is firmly secured to the cover plate 7 by fastening means 19. The piston 16 of each of the servo-motors has a piston rod 15 secured to the adjacent lug 23 of the ring 14 by means of a pin 24. The forward travel of each piston 16 is limited by adjustable stops 20, while the rearward travel thereof is likewise limited by an adjustable stop 22. Fluid under pressure may be admitted to and discharged from the chambers within

the cylinders 17 at the opposite ends of the pistons 16, through suitable fluid admission and exhaust pipes 21.

During normal operation of the unit, the 5 turbine regulator functions to admit fluid to the servo-motors in a well known manner and to thereby adjust the inlet guide vanes 6 to admit water from the supply conduit 3 through the transition space 5 to the rotor 10 2. The water after leaving the rotor 2, is delivered to the draft tube 4 and from thence to the tail-race in an obvious manner. The movement of the guide vanes 6 is limited by the adjustment of the stops 20, 22 and the 15 reaction resulting from shifting of the guide vanes 6 is transmitted to the cover plate 7 through the bracket 18.

By disposing the servo-motors closely adjacent to the main shaft 25 and within the 20 annulus of the series of vanes 6, the diameter of the pit may obviously be reduced to a minimum and the guide vane adjusting arms 12 and links 13 are freely accessible without obstruction by the servo-motor structure. The pit may obviously have a relatively thin lining in view of the fact that the servo-motors are not associated therewith in any manner. The bracket 18 may 25 also be omitted from the structure and formed integral with the servo-motor cylinders 17, or the cylinders may be attached directly to the cover plate 7, without departing from the present invention.

Since the servo-motor cylinders 17 are 30 ordinarily supplied with fluid under pressure derived from a common source, and are interconnected by means of piping, the location of these cylinders at one side of a plane containing the rotor axis, simplifies the arrangement of the fluid conducting pipe and avoids undesirable obstruction of the pit on the opposite side of said plane. By virtue 35 of the fact that the servo-motors deliver actuating motion substantially in a tangential direction with respect to the arcs of movement of the pins 24, undesirable binding of the parts and consequent loss of power, are eliminated.

It should be understood that it is not 40 desired to limit the invention to the exact details of construction and operation herein shown and described, for various modifications within the scope of the claims may occur to persons skilled in the art.

It is claimed and desired to secure by 45 Letters Patent:

1. In combination, a casing comprising a 50 cover plate, a rotor within said casing, an annular series of guide vanes within said 55 casing and surrounding the axis of said rotor, a shifting ring for simultaneously ad-

justing said vanes, said ring having actuating pins associated therewith on opposite sides of the rotor axis, and a pair of servomotors supported upon said cover plate and 60 operatively associated with said pins, said servomotors being disposed substantially at one side of a plane containing the rotor axis and delivering actuating motion substantially tangentially relative to the axis of movement of said pins. 70

2. In combination, a casing comprising a cover plate, a rotor within said casing, an annular series of guide vanes within said 75 casing and surrounding the axis of said rotor, a shifting ring for simultaneously adjusting said vanes, said ring having actuating pins associated therewith on opposite sides of the rotor axis, a bracket supported by said cover plate within said ring, and a pair of servomotors carried by said bracket and operatively associated with said ring, said servomotors being disposed substantially 80 at one side of a plane containing the rotor axis and delivering actuating motion substantially tangentially relative to the axis of movement of said ring. 85

3. In combination, a casing comprising a cover plate, a rotor within said casing, an annular series of guide vanes within said 90 casing and surrounding the axis of said rotor, a shifting ring for simultaneously adjusting said vanes, said ring having diametrically opposite actuating pins located within the ring, and a pair of double acting 95 servo-motors supported upon said cover plate and operatively associated with said pins, said servomotors being disposed entirely at one side of a plane containing the rotor axis and delivering actuating motion 100 tangentially relative to the arcs of movement of said pins.

4. In combination, a casing comprising a cover plate, a rotor within said casing, an annular series of guide vanes within said 105 casing and surrounding the axis of said rotor, a shifting ring for simultaneously adjusting said vanes, said ring having diametrically opposite actuating pins located within the ring, a bracket supported by said 110 cover plate within said ring, and a pair of double acting servo-motors carried by said bracket and operatively associated with said ring, said servo-motors being disposed entirely at one side of a plane containing the 115 rotor axis and delivering actuating motion tangentially relative to the arcs of movement of said pins.

In testimony whereof, the signature of the inventor is affixed hereto.

VICTOR E. ANDERSON.
